UNITED STATES PATENT OFFICE.

FRANK L. WEISS, OF BRONX, NEW YORK.

INCANDESCENT ELECTRIC BULB.

Application filed February 23, 1926. Serial No. 90,023.

This invention relates to incandescent electric lamp, and has for an object to provide a lamp having a plurality of filaments so as to be capable of use for various degrees of illumination.

Another object is to provide a lamp having a plurality of chemically treated filaments so as to be capable of use for illuminating in various colors.

10 A further object of this invention resides in the novel arrangement and construction thereof, and for further comprehension of the invention, and of the objects and advantages thereof, reference will be had to the following description and accompanying drawing, and to the appended claims in which the various novel features are more particularly set forth.

Fig. 1 of the drawing shows a perspective view of a lamp embodying this invention.

Fig. 2 shows a top elevational view of the lamp shown in Fig. 1.

Fig. 3 indicates the position of the contacts in the socket in which the lamp is to be inserted, the external wiring to these contacts, and the relation of the lamp contacts to the socket contacts.

Fig. 4 shows a fragmentary vertical sectional view of a slightly modified form, in which the pin for fastening lamp in socket are adjustable.

Fig. 5 shows a horizontal sectional view taken on the line 5—5 of Fig. 4.

Fig. 6 shows a fragmentary vertical sectional view taken on the line 6—6 of Fig. 5.

The lamp shown on the drawing is constructed with a plug portion 10, and a bulb portion 11, the plug portion being provided with three contacts 12, 13 and 14 at its upper end, and on its sides with projecting pins 15, and 16, which are for engagement with bayonet slots in a suitable socket in which the lamp is adapted to be inserted.

Within the bulb portion 11, a central post 17 of glass, or other suitable insulating material extends from the socket portion downwards, and at its lower extremity supports a plurality of arms 18, preferably at right angles to the said post 17. A lead 19 extends from the contact 12, thru the post 17, emerging from the bottom thereof, and is suitably connected as at 20 to a filament 21 supported by the arms 18, and terminating at 22. A lead 23 extends from the contact 13 thru the top portion of post 17, and thereafter projects outwards, and suitably con-

ncts as at 22 to a filament 25, which is electrically connected at 22 to filament 21, and this filament 25 terminates at 24, where it is electrically connected to lead 26 from the contact 14.

With this structure various degrees of illumination may be obtained. For example, filament 21 may be a twenty-five watt filament, and 25 may be a fifty watt filament. With this arrangement three degrees of illumination is possible, viz, if the lamp plug is connected in the socket so that the current acts between contacts 12, and 13, the twenty-five watt filament will be illuminated, acting between 13, and 14, the fifty watt filament will be illuminated, and acting between 12, and 14, both the twenty-five and fifty watt filaments will be illuminated, being equivalent to a 75 watt filament. It will readily be seen that the filaments may be arranged to give desired degrees of illumination. Furthermore filaments giving out colored rays may be used, so that the lamp may be used to illuminate in various colors.

It may be of interest to consider the necessary arrangement of the contacts in the lamp socket, which receives the lamp, to permit of the various connections. Referring to Fig. 3, the line 27 and 28 leads to the sockets, which connect to two contacts 29, and 30. The contacts are arranged on a circle of the same diameter as used for the contacts 12, 13, and 14 of the lamp plug, and should be spaced 120° arc apart. As shown in Fig. 3, contacts 29 and 14 connect, simultaneously with 30, and 12. The sockets are arranged with three sets of bayonet slots to accommodate pins 15, and 16, at every one-third turn. The lamp may be removed from the position shown, given a one-third turn to the right and replaced, then 13 will connect with 29, and 14 with 30. Another one-third turn will result in 12 connecting with 29, and 13 with 30.

The modification shown in Figs. 4, 5, and 6, shows the pins 15, and 16, radially and vertically adjustable. A ring 31 is fixed in the plug, has screw 32 with heads exterior to the plug, engaged in slots 33 of supports 34, and nuts 35 on the bottom thereof. The supports carry the pins which are engaged in vertical slots 36, and are provided with lock screws 37 and nuts 38.

While I have illustrated and described my invention with some degree of particularity, I realize that in practice various alterations

therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

- 10 1. In a device of the class described, having a plug portion with side openings, the combination of a ring fixed to said plug portion, screws passing through said plug portion and ring, said screws having heads exterior to the plug, supports formed with slots, the bottoms of said screws passing through said slots, nuts on the bottom of said screws, said supports being also formed with vertical slots, pins engageable in said vertical slots, and lock screws and nuts engageable with said pins projecting through the side openings of said plug.
- 15 2. In a device of the class described, having a plug portion, the combination of a ring fixed to said plug portion, screws passing
- 20
- 25

through said plug portion and ring, said screws having heads exterior to the plug, supports formed with slots, the bottoms of said screws passing through said slots, nuts on the bottom of said screws, said supports being also formed with vertical slots, pins engageable in said vertical slots, and lock screws and nuts engageable with said pins and said supports.

3. In a device of the class described, having a plug portion with side openings, the combination of a ring fixed to said plug portion, screws passing through said plug portion and ring, supports formed with slots, the bottoms of said screws passing through said slots, nuts on the bottom of said screws, said supports being also formed with vertical slots, pins engageable in said vertical slots, and lock screws and nuts engageable with said pins and said supports, said pins projecting through the side openings of said plug.

In testimony whereof I have affixed my signature.

FRANK L. WEISS.
